UNITED STATES PATENT OFFICE.

EDWIN B. WILHELM, OF HIGHLAND PARK, MICHIGAN.

WRAPPER-CUTTING MACHINE.

Substitute for application Serial No. 269,800, filed January 6, 1919. This application filed May 13, 1926.
Serial No. 108,955.

The present application is a substitute for application Serial Number 269,800, which application was forfeited July 29, 1921, for failure to pay the final fee.

5 In the manufacture of cigars, stogies and other wrapped tobacco products, it has been the practice to manually cut the wrappers therefor, and such cutting operations require considerable skill and precision in order to 10 avoid waste by not having the wrappers too small or too large. Then again, when cut by hand it is practically impossible, without some guiding means to have all wrappers of a uniform size, which results in the 15 wrapped appearance of one cigar being different from another, and this is not a desideratum, particularly when a certain brand of cigars, particularly of a good grade is to be produced.

20 My invention aims to provide a wrapper cutting machine by which tobacco leaves may be expeditiously and economically cut and trimmed to produce uniform and properly shaped wrappers, the machine, after 25 being set for a predetermined wrapper, requiring no attention whatsoever, other than placing the tobacco leaf or strip in position to be operated upon.

My invention further aims to provide a 30 machine of the above type involving novel means for laterally shifting a leaf or strip of tobacco so that straight cuts may be made in a desired direction, and associated with such shifting means is a novel mechanism 35 for shifting a cutter or similar instrument for curvilinear cuts, as a continuation of the straight cuts. As a whole, a leaf shifting means and cutter guiding means are timed 40 for a sequence of operation which eventually severs a wrapper of desired shape from a leaf or strip of tobacco placed in the machine, and with the tobacco stock properly positioned, it is possible to sever wrappers from superposed leaves or laminated stock 45 placed in the machine.

My invention will be hereinafter more fully considered and reference will now be had to the drawing, wherein—

Figure 1 is a front elevation of the tobacco 50 wrapper cutting machine;

Fig. 2 is a plan of the same, partly broken away;

Fig. 3 is a cross sectional view of the machine taken on the line III—III of Fig. 2;

Fig. 4 is a diagrammatic plan of one of the main driving gear wheels of the machine;

Figs. 5 and 6 are similar views of other gear wheels of the machine;

Fig. 7 shows a developed view of a portion of a cam cylinder forming part of the machine, said view being to a certain extent a chart as to the operations of the machine;

Fig. 8 is an end view of the cam cylinder;

Fig. 9 is a horizontal sectional view of the line IX—IX of Fig. 3, showing horizontal 65 cam members; and

Figs. 10 to 24 inclusive illustrate in conjunction with Figs. 7, 8 and 9, the cutting of a wrapper in its different stages and the operations incident thereto.

The machine may be characterized by co-operating organizations as a bed frame having a reciprocatory carriage and table with a work board; a main frame and cam cylinder; a spindle housing and operating mechanism, and a cutter spindle and elevating mechanism, but in describing these organizations by aid of the views above referred to, I desire to point out that the same are intended as merely illustrative of a machine 80 by which my invention may be put into practice, therefore I do not care to confine myself to the precise construction and arrangement of parts other than defined by the appended claims.

In the drawings, the reference numeral 1 denotes a bed frame having one end thereof provided with parallel side rails or shears 2 for a reciprocable carriage 3, said carriage having its rear edge provided with a set of 90 rearwardly extending arms 4 having confronting anti-frictional rollers 5 at the rear ends thereof. 6 denotes a dove-tailed groove or guideway in the carriage 3 for a reciprocable table 7 held against vertical displacement by the side walls of the groove or guideway 6. Suitably fixed to the upper surface of the table 7 is a work holder or board 8 upon which a tobacco leaf or strip may be correctly positioned so that a wrapper 95 may be cut from the same. The table 7 is adapted to be reciprocated transversely of the carriage 3 or shifted in a direction at right angles to the movement of the car-

riage 3, and said table has depending parallel flanges or a guideway 9 extending through the carriage 3, as best shown in Fig. 3. Movable between the flanges 9 is an anti-frictional roller 10, carried by the forward end of a lever 11 that extends rearwardly over the bed frame 1, said lever being pivoted by a stud or screw 12 on a slide block or bearing 13 in a longitudinal depressed portion 14 of the bed frame 1. Loose on the stud 12, between the lever 11 and the slide block 13, is a slotted end of an arm 15, said arm being pivoted on the bed frame 1, as at 16. Extending through the outer end of the arm 15 is a bolt 17 that has its head in a segment shaped groove or recess 18 of the bed frame 1, and the upper end of the bolt 17 is provided with a winged thumb nut 19 so that after said arm has been adjusted, it may be locked relative to said frame 1, and thus hold the slide 13 in an adjusted position to increase or decrease the leverage or shifting action of the lever 11. The extreme rear end of the lever 11 is slotted to engage a stud 20 carried by a slide nut 21 in another depressed portion 22 of the frame 1, and on the upper end of the stud 20 is an anti-frictional roller 23.

Considering the main frame and cam cylinder of the machine, the reference numerals 24 and 25 denote the side arms or bearings of an inverted U-shaped frame 26 on the rear end of the bed frame 1, and journaled in the side arms 24 and 25 are alining spindles 27 and 28 respectively, the spindle 27 having the outer end thereof provided with a grooved pulley or driven wheel 29 and the outer end of the spindle 28 provided with a beveled gear wheel 30. Any suitable means, as a belt or cable 31, may be employed for transmitting power to the spindle 27.

32 denotes confronting cam heads on the inner ends of the spindles 27 and 28, said heads having the outer side walls thereof provided with cam grooves 33 to receive the rollers 5 of the arms 4, said arms being slideable in brackets 34, carried by the arms 24 and 25 of the main frame 26. When the cam heads 32 are rotated, the arms 4 are reciprocated to impart movement to the carriage 3, as defined by the contour of the cam grooves 33 in the heads 32. On the inner side walls of the heads 32 are sets of lugs 35 adapted to engage in sets of notches 36 provided therefor in the ends of the cam cylinder 37 placed between the heads 32 and held by set screws 38 or similar fastening means. The lugs 35 are in a common plane and by moving the set screws 38 the cam cylinder 37 may be shifted from between the heads 32 and replaced by another cylinder which may produce a different action in connection with the machine from that of the cam cylinder shown. With the cam cylinder 37 removed, the pulley 29 can be removed

from the spindle 27 and the beveled gear wheel 30 removed from the spindle 28, and then the cam heads 32 shifted towards each other so as to be removed from the machine and other suitable cam heads substituted therefore. This constructive arrangement of the cam cylinder and its supporting head permits of all three elements being rotated in synchronism and other elements substituted therefor when it is necessary to change the action of the machine to obtain wrappers of desired size and contour.

39 denotes a cam groove in the periphery of the cylinder 37 and extending into said cam groove is the anti-frictional roller 23 at the rear end of the fulcrumed lever 11. When the cam cylinder 37 revolves said cylinder imparts an oscillatory movement through the fulcrum lever 11 and the table 7 is shifted on the carriage 3, independent of the movement of the carriage and the movement of the table defined by the contour of the cam groove 39.

40 and 41 denote superposed brackets supported by and extending forwardly from the main frame 26 and journaled in these brackets is a vertical shaft 42 that has the upper end thereof provided with horizontal gear wheels 43 and 44, the gear wheel 43 being one of a train of gears for transmitting power to the shaft 42 and is consequently pinned or otherwise fixed to said shaft and also to the gear wheel 44, which is of the mutilated type designed for intermittently transmitting power, the gear wheel having two sets of spaced apart teeth 45 and 46.

47 denotes a horizontal gear wheel meshing with the gear wheel 43, said horizontal gear wheel being supported by the brackets 40 and meshing with a similarly disposed gear wheel 48 mounted on the upper end of a vertical shaft 49 journaled in bearings 50, carried by the arms 25 and the bracket 40 of the main frame 26. On the lower end of the vertical shaft 49 is a beveled gear wheel 51 meshing with the driven beveled gear wheel 30, and it is through the medium of these beveled gear wheels, the shaft 49, and the horizontal train of gears that the vertical shaft 42 is driven by and in synchronism with the cam cylinder 37.

52 denotes a vertically disposed housing shaft journaled in the outer end of the bracket 40 and having the upper end thereof provided with a small gear wheel 53 and a toothed brake wheel 54. The small gear wheel 53 is adapted to have movement imparted thereto by the teeth 45 and 46 of the gear wheel 44 and the toothed brake wheel 54 is engaged by a resilient detent 55 carried by an extension 56 of the bracket 40, as best shown in Fig. 1. This resilient detent and the toothed brake wheel 54 are adapted to prevent accidental or over-running rotation of the housing shaft 52.

57 denotes the hub of a cylindrical housing 58, said housing having the lower end thereof open and provided with an internal rack 59. The hub 57 is loose on the housing 5 shaft 52 and contiguous to the upper end of said hub is a peripheral flange 60 supporting a small gear wheel 61 and a toothed brake wheel 62, these wheels being fixed for rotation with the hub 57. The small gear wheel 10 61 is adapted to have movement imparted thereto by teeth 63 and 64 of a large horizontal gear wheel 65 keyed or otherwise fixed on the vertical shaft 42 and somewhat similar to the gear wheel 44. The only difference is that the lower face of the gear wheel 65 has a beveled gear wheel portion 66 meshing with a pinion 67 rotatably supported by an extension 68 of the bracket 40.

The pinion 67 meshes with a beveled gear wheel portion or rack 69 of a horizontal reversing gear wheel 70 loose on the shaft 42 above the bracket 41. The gear wheel 70 meshes with a gear wheel or toothed portion 71 of the hub 57 and when said hub is not 25 revolved by the gear wheel 65 it may be revolved by the reverse gear wheel 70.

71 denotes another resilient detent carried by the extension 56 of the bracket 40 engaging the toothed brake wheel 62 and preventing an accidental or overrunning movement of the housing hub 57. To prevent lateral or swaying movement of the housing 58 said housing is engaged by anti-frictional balls 72 suitably retained in a race in the 35 outer end of the bracket 41, as best shown in Fig. 3.

73 denotes a crank fixed on the lower end of the housing shaft 52, and assisting in supporting the same relative to the brackets 40 and 41. In the outer end of the crank 40 73 is journaled a cutter spindle 74 provided with a pinion 75 meshing with the rack 59 of the housing 58. The cutter spindle 74 extends below the housing 58 and has the lower end thereof reduced as at 76, and a cutter holder 77 slidable on the spindle 74, said spindle having a transverse pin 78 extending into a slot 79 in the holder, so as to establish a driving relation between the spindle and the holder and at the same time permit of said holder being raised and lowered relative to the spindle.

80 denotes a horizontal disk on the upper end of the cutter holder 77 and engaging the lower face of said disk are anti-frictional rollers 81 on the forked or bifurcated end 82 of an arm 83 said arm being pivotally held by the lower end of a hanger forming part of the bracket 41. The inner or rear end 50 of the arm 83 is adapted to be engaged by cams 85 carried by a horizontal wheel 86 mounted on the lower end of the vertical shaft 42, and it is through the medium of the wheel 86 that the arm 83 can be actuated to 60 raise the cutter holder 77, said cutter holder

having its disk 80 normally held by engagement with the arm 83 by a coiled compression spring 87 in the holder 77 and encircling the reduced end 76 of the spindle 74. The lower end of the holder 77 has a crank 78 portion 88 affording a bearing for a disk cutter 89, said disk cutter being adjustable to and from its bearing or the axis of the holder 77.

In considering the operation of the machine, it is thought that the same can be better understood by considering the carriage, table and work holder as a platen shiftable forward, backward, to the left and to the right, and on the work board of which may be marked or otherwise indicated, a territory or zone in which the marginal edges of a flattened tobacco leaf or strip must be placed in order that the machine may cut out a wrapper of the contour disclosed by Figs. 10 to 24 inclusive.

Furthermore, that the cutter spindle 74 may be considered an axis A about which the cutter 89 may be swung, and the housing shaft another axis B about which the cutter spindle 74 may be swung.

All of the straight or right angular movements of the platen, the curvilinear movements of the cutter, together with the raising and lowering of the same, have been developed and illustrated as accurately as possible in Figs. 7 to 24 inclusive, which point out a series of operations numbered from 1 to 22 inclusive. These numbered operations are associated with the production of a wrapper from the first operation to the last, all of which have been pictured in Figs. 10 to 24 inclusive. The numbered operations which take place in the production of the wrapper have been indicated in connection with Figs. 4 to 9 inclusive and particularly Fig. 7 showing a developed view of the cam cylinder 37.

Assuming that a tobacco leaf has been correctly positioned on the platen and the machine placed in operation, No. 1 cut is that of the cutter spindle 74 rotating a quarter of a revolution to swing the cutter 89 around the axis A, while the platen is at rest. This is accomplished by the gear wheels 44 and 65 being out of mesh with the gear wheels 53 and 61, the gear wheels 53 and 61 locked by the resilient detents 55 and 71, a few of the teeth of the gear wheel 70 imparting movement to the gear wheel 57 of the housing hub 57 causing the housing and its rack to rotate the cutter spindle 75 a quarter of a revolution. While this takes place the resilient detent 71 yields relative to the gear wheel 61, and with the cutter 89 offset relative to the axis A, cut No. 1 is produced.

The next cut, No. 2, is a straight cut produced by the cutter spindle 74 remaining stationary, while the platen is shifted through the medium of the cam heads 32,

rollers 5, and arms 4. After the completion of this No. 2 cut, the cutter is raised by one of the cams 85 engaging the arm 83 and bodily lifting the cutter holder 37. With the cutter momentarily elevated operations take place as indicated by Nos. 4 and 5, causing the cutter to make a half revolution about the axis A while the platen moves back. Then the cutter is lowered by the cam 85 moving out of engagement with the arm 83, and the machine is in condition for producing operation No. 7. This is a semi-circular cut, the starting of which is shown in Fig. 11 and concluded in Fig. 12. The cutter bearing 88 has been placed in the same vertical plane as the crank 73 and the gear wheels 44 and 65 imparting movement to the housing shaft 52 and the housing hub 57, cause these two elements to simultaneously revolve a half revolution while the platen is at rest.

Next in order is a straight cut No. 8 which is accomplished by the cutter spindle being locked and the platen moving to the right, this being in an opposite direction to that which produces the straight cut No. 2. Following the short cut No. 9, there is a small curved cut No. 10, and so on until a wrapper of desired contour is produced.

In view of the explanatory notes associated with Figs. 4 to 24 inclusive, it is thought unnecessary to rehearse all of the steps and operations of producing a wrapper, which, as shown has rounded or semi-circular ends with the curvature at the outer end of the wrapper extending beyond the side edge thereof represented by cut No. 2. The semi-circular inner end of the wrapper also extends beyond that side of the wrapper represented by straight cut No. 9, and said semi-circular cut terminates in an inscribed cut which produces a pad for closing the wrapper at the inner end of the cigar filler, when spirally wound thereon. This wrapper outline is of conventional form and one of many resorted to in the production of various styles of cigars, so it is with this thought in view that the cam cylinder 37, cam heads 32, cam wheel 86, gear wheels 44, 65 and 70 together with the adjustability of the lever 11, can be changed so that a wrapper of desired outline may be cut by the machine. It is also possible to substitute another tool for the cutter 89 so that various kinds of tracery may be delineated on a piece of work carried by the platen of the machine. It is only a question of developing the cam grooves 23 and 39, the toothed gear wheels 44, 65 and 70 and timing the various operations to obtain any desired cut or mark in or on a piece of work.

What I claim is:—

1. The combination of a cutter adapted for cutting out wrappers by straight and curvilinear cuts, an intermittently operated

platen for effecting straight cuts by said cutter, operating means for said platen including a cam cylinder and heads with arms and a lever for moving said platen, and means for effecting curvilinear cuts by said cutter when said platen is stationary, said means being operable from one end of the cam cylinder of said platen operating means.

2. The combination of a wrapper holder, a cutter operable above said holder, means adapted for operating said cutter, said means comprising an intermittently actuated shaft for swinging said cutter with a large radius, and a rotary spindle for swinging said cutter from a small radius.

3. The combination of a wrapper holder, a cutter operable above said holder, means adapted for operating said cutter, said means comprising an intermittently operated shaft for swinging said cutter with a large radius, an intermittently operated housing about said shaft, and a rotary spindle supported from said shaft and actuated by said housing for swinging said cutter with a small radius.

4. Means for cutting out cigar wrappers, comprising a spindle, an offset cutter at the lower end thereof, means having an axis parallel to said spindle for imparting a rotary movement to said spindle to swing said cutter about said spindle as an axis, and means adapted for bodily swinging said spindle about the axis of the rotating means of said spindle.

5. Means for cutting out cigar wrappers comprising a shaft, means adapted for rotating said shaft, a housing about said shaft, means adapted for rotating said housing in either direction, a cutter spindle supported by said shaft in said housing and adapted to be bodily swung about said shaft as an axis, an offset cutter carried by said spindle, and means effecting a rotary movement of said spindle from a rotary movement of said housing independent of said shaft.

6. Cutting means as characterized in claim 5 wherein means is constructively arranged for raising and lowering said cutter relative to said spindle.

7. In a cigar wrapper cutting machine, the combination of a cutter adapted for making curvilinear cuts, a platen for holding an uncut wrapper and adapted to be shifted to cause said cutter to make straight cuts, means for imparting movement to said platen, said means including cam heads for effecting movement of said platen to cause said cutter to make a straight cut, and a cam cylinder between said heads for effecting movement of said platen to cause said cutter to make a straight cut at an angle to the first mentioned cut.

8. In a cigar wrapping machine, the combination of a cutter adapted for making curvilinear cuts, a platen for holding an un-

cut wrapper adapted to be shifted to cause said cutter to make straight cuts, and means for imparting movement to said platen, said means including cam heads defining the movement of said platen in one direction, a cam cylinder between said heads adapted for moving the platen in another direction, and means between said platen and said cam cylinder adapted to be adjusted to define the movement of said platen by said cam cylinder.

In testimony whereof I affix my signature.

EDWIN B. WILHELM.
